UNITED STATES PATENT OFFICE.

ALEXANDER MASZCZYK, OF CHICAGO, ILLINOIS.

COMBINATION MACHINE VISE.

Application filed March 23, 1923. Serial No. 626,997.

To all whom it may concern:

Be it known that I, ALEXANDER MASZCZYK, a citizen of the United States, and resident of Chicago, in the county of Cook and State 5 of Illinois, have invented certain new and useful Improvements in a Combination Machine Vise; and I do hereby declare that the following is a full, clear, and exact description thereof.

10 This invention relates to vises. It comprises a plate adapted to be secured to a machine bed or like support, a cylindrical table integral therewith, a stud carried by the table, and a vise proper, the bed of 15 which is swiveled on the stud and has a guideway therein for the reception of a slide which is movable by a screw to cause a jaw pivoted thereon to approach a jaw fixed to the bed.

20 The primary object of the invention is the provision of a vise adapted to be used on milling machines, grinders, drill presses, and the like devices, which may be conveniently secured to a bed-plate which is 25 adapted to securely retain stock of various shapes. The free jaw may be locked rigid with the slide and then is disposed parallel to the fixed jaw, or the free jaw may be inclined to receive the fixed jaw so as to 30 grip material of wedge shape. The mounting of the vise bed in the manner of a turret facilitates the usage of the device in different positions of adjustment, so that it 35 presents the material worked on advantageously for the actions of the milling or other machine. The bed may be secured rigidly to the table, so that a positive and effective grip is exerted on the material 40 which is incapable of movement in any direction.

An object of the invention is the provision of a vise which may be used for bending purposes. The movable jaw may be rotated on its pivot to present a nose towards 45 the fixed jaw, the nose being rounded to facilitate the bending operation. If desired, the movable jaw may be removed entirely and replaced by a roller, as the pivot carried by the slide is adapted for this purpose, so that the bending operation may be 50 carried out with the greatest convenience.

An object of the invention is the provision of a device which may, if desired, be used as a jack. The bed may be disposed 55 vertically and the movable jaw may then be used for lifting purposes.

With the above and other objects in view, which will appear as the description proceeds, the invention resides in the novel construction, combination and arrangement of parts substantially as hereinafter described and more particularly defined by the appended claims, it being understood that such changes in the precise embodiment of the herein disclosed invention may be made as 60 65 come within the scope of the claim.

In the accompanying drawing is illustrated one complete example of the physical embodiment of the present invention constructed according to the best mode so far 70 devised for the practical application of the principles thereof.

Figure 1 is a plan view of the device, showing in dotted lines the reversed position of the movable jaw, and indicating by 75 a broken line the position of a roller which may be substituted for the movable jaw.

Fig. 2 is a section on the line 2-2 of Fig. 1;

Fig. 3 is a plan of the table and parts 80 therebelow with the vise proper removed:

Figure 4 is an end view of the entire mechanism;

Figs. 5, 6 and 7 are sections on the lines 5-5, 6-6, and 7-7 of Fig. 2; and 85

Fig. 8 is a plan showing the disposal of the jaws with a wedge-shaped piece of work therebetween.

In order that the vise may be used to advantage in connection with milling machines, 90 grinders, drill presses, and the like devices, a plate 10 is provided having slots 11-11' therein, adapted to receive bolts for securement to the bed-plate of the machine. Suitably secured to the lower face of plate 10 is 95 a bar 12 which may be disposed in a groove in the bed-plate. By means of a reduced neck 13 the plate 10 is integrally connected with a cylindrical table 14 having a beveled lower side 15. The table is bored to receive 100 an enlarged portion of the stud 16 and a chamber 17 is provided in the plate 10 immediately below the bore.

The vise proper has a bed 18 provided with an opening 19 receiving the stud 16. 105 The bed is thus swiveled on the table 14 and may be moved to any desired position of rotation about the stud 39. This facilitates usage of the device with machines of various types, as it is adapted to present the material 110 in an advantageous position for action by the machine. The bed 18 is provided with

longitudinal flanges 20—20' having holes 21 therein for the reception of hook bolts 22, the heads of which are adapted to grip the beveled lower face of table 14. The nuts 23 on the bolt rest on the flanges. By means of the bolts the vise bed may be secured rigidly in any desired position of rotation about the stud and the resulting rigid relation of parts makes secure the holding of the material in position for operation by the machine in connection with which the vise may be used. Additional openings 24 are provided in the flanges 20—20'. If desired, the bolts 22 may be removed and the bed may be used independently of the table, in which case the holes 24 are useful for the purpose of bolting the vise bed in desired position. The vise bed has a longitudinal channel 25 therein and a recess 26 intersecting the channel. The upper part of the recess is filled by block 27 threaded to a screw 28 having a squared end 29 by which it may be rotated to travel through the channel. A jaw 30 is formed on one end of the bed and is secured by screws 31 to a clamping plate 32 having intersecting gripping grooves 33 in its face. A vertical cavity 34 extends from in front of the plate 32 to the top of table 14. It is used for objects which it is desired to dispose vertically for working purposes. The work may be inserted into the cavity and disposed conveniently in front of the gripping plate 32. The vise bed has a longitudinal guideway 35 of inverted T-shape in cross-section into which is fitted a slide 36 having at its outer end a depending projection 37 in which the screw 28 is secured for rotation by means of a pin 38 fitting into an annular groove 37'. On the rotation of the screw the slide 36 is caused to approach or recede from fixed jaw 30, the screw being substantially in threaded relationship with the vise bed by means of block 27. Formed integrally on the inner end of slide 36 is a pivot 39 on which movable jaw 40 is rotatably mounted. A clamping plate 41 is secured to the jaw by means of screws 42. A recess is provided in the upper face of jaw 40 for the reception of a washer 43 which is countersunk to receive a screw 44 threaded into pivot 39. The jaw 40 is provided at its outer end with a rounded nose 45 having an opening therein in which a

screw 46 is placed, the screw extending into slide 36 and rendering jaw 40 rigid therewith. 55

When screw 46 is in position, the clamping plates 32 and 41 are disposed in parallel relation. If desired, screw 46 may be removed and the clamping plate 41 may be disposed at an angle to clamping plate 32 as shown in Fig. 8. A wedge-shaped piece of work 47 may then be gripped by the jaws. It is apparent, therefore, that the material is effectively clamped and secured against displacement, irrespective of the position of the jaws, which are adapted to effectively grip objects of various shapes. 60

If desired, movable jaw 40 may be rotated to dispose the nose 45 adjacent to clamping plate 32 as shown in dotted lines in Fig. 1. The rounded nose may then be used for the purpose of bending, as the nose and clamping plate 34 grip the stock which may be shaped about the rounded nose. By removing screw 44 pivot 39 may be utilized for supporting a roller in the position shown by the broken line in Fig. 1. The roller also may be used for bending purposes. 70

The vise may be separated entirely from table 14 and may be used in a vertical position, either with or without the table. It may also be used as a jack, in which case jaw 40 is operative for lifting vertically. 80

I claim:—

85
A machine vise comprising a bed-plate having a table integral therewith, a stud carried by said table, a vise bed pivoted upon said stud, locking means for temporarily holding said vise bed and table together, said vise bed having a movable slide 90
adjustably carried thereby, a stud projecting upwardly from said slide and rigid therewith, a block having a clamping face and pivotally mounted upon said stud with the 95
stud closely adjacent said clamping face, said block having a rearward extension, said extension and said slide having registering apertures, a screw passing through said apertures, and a stationary gripping jaw carried 100
by said vise bed.

In testimony that I claim the foregoing I have hereunto set my hand at Milwaukee, in the county of Milwaukee and State of Wisconsin.

ALEXANDER MASZCZYK.
